UNITED STATES PATENT OFFICE.

JACQUES PIERRE DE BRAAM, OF PARIS, FRANCE.

AUTOMATIC RAILWAY SIGNALING APPARATUS.

1,111,522.

Specification of Letters Patent. Patented Sept. 22, 1914.

Application filed January 30, 1913. Serial No. 745,115.

To all whom it may concern:

Be it known that I, JACQUES PIERRE DE BRAAM, subject of the Queen of the Netherlands, residing at 5 Rue Davioud, Paris, in the Republic of France, have invented new and useful Improvements in Automatic Railway Signaling Apparatus, of which the following is a specification.

This invention has for its object to provide an improved mechanism for operating automatic warning and indicating apparatus for stopping trains in front of a signal at danger, of the kind comprising as usual a fixed track detent located at one side of the track rail, and a movable track detent controlled by the signal at the other side of the track rail, each of these detents corresponding to a lever, and the two levers being connected to a locking or engaging mechanism in such a manner that the application of the brakes or the release of the signals can be effected only in case both levers are raised.

In existing apparatus of this type the connection of the two levers is produced by an arrangement of spring bolts which connects the levers or allows them to be independent according as the two levers are raised together, or only one lever is raised. The double bolt is arranged on the shaft or rotary sleeve which effects through gearing, wiring or rodding the application of the brakes or the release of the signals.

Now according to the present invention the locking mechanism which connects the two levers is so constructed as to constitute at the same time and in a direct manner the engaging or releasing device for applying the brakes or operating the warning signals. This construction has many advantages:—

1. It reduces considerably the number of springs used in the entire installation because only one spring is employed for actuating the mechanism for releasing the warning signals or applying the brakes, and for operating the locking mechanism that connects the two levers. 2. The hitherto existing gearing, wiring or rodding is dispensed with between the connected levers and the device for applying the brakes and releasing the warning signals. 3. The entire arrangement of devices (mechanism for locking the levers and mechanism for applying the brakes or releasing the warning signals) may be assembled in a very small space and completely protected in a casing from dust, frost etc.

A practical construction according to this invention of connecting mechanism between the mechanism for locking the levers and the mechanism for taking off and applying the brakes and locking and releasing the warning signals is illustrated by way of example in the accompanying drawings in which:

Figures 1 and 1^a constitute a longitudinal section, and Fig. 2 is a cross section on the line 2—2 of Fig. 1, of the improved connecting mechanism.

As shown, the levers *a* which effect the disengaging or releasing operation for the purpose of actuating the warning signals or the brakes by impacting against detents located on the track, are adapted to rotate in a direction opposite to that of the travel of the train, on pivot pins *c* mounted in arms *d* projecting from sleeves *f* that can rotate on a fixed axle *g*. Motion in the reverse direction that is to say, in the direction of the travel of the train is rendered impossible by the usual means. The levers in their movement cause the arms *d* to rock. The sleeves *f* are separated from each other by a washer or disk *h* in such a manner as to prevent the rotation of one sleeve from being transmitted to the other sleeve.

Each of the sleeves *f* carries in a part *i* of reduced diameter a cam *k* (Fig. 2), and in the path of each cam there is located the end of a lever *m* fulcrumed on a pin *l*. The levers *m* are connected together as shown in Fig. 2 by means of the joint *l* in the manner of a pair of scissors. *m'* is a spring which keeps the upper ends of the levers *m* normally engaged in a piston *o* that is slidable in a cylinder *p*. *q* is a spring having a tendency to push the piston *o* to the right. The piston *o* has a rod projecting outward to which a pulling member *r* is attached that leads to the brake or warning signals.

When the apparatus is at rest the piston *o* is held by the scissor levers *m* in the position shown in Fig. 1. If only one of the levers *a* is struck by a detent, the corresponding sleeve *f* will be rotated and the cam *k* of said sleeve will cause the corresponding lever *m* to rock to an extent sufficient to cause the said lever to move out of the piston *o*. But since the other lever *a* has not been actuated, the corresponding scissor lever *m* will remain in engagement in the piston *o* so that the latter will retain its position. If however the two levers are struck simultaneously by track detents, the two scissor

levers *m* will be disengaged by the cams *k* from the piston *o* and the piston *o* will be pushed toward the right by the spring *q* so that the pulling member *r* will be caused to 5 actuate in the known manner the brakes or the warning signals.

The driver in returning the warning device into its normal position of rest, causes by operating the flexible pulling member, 10 the piston to move back from the right to the left, and thereby returns the apparatus into the position shown in Fig. 1, thereby effecting a reengagement of the scissor levers. In the improved apparatus a single 15 engaging operation serves for connecting together the levers *a* and also for operating the brakes or the warning signals. In this case the gearing, wiring or rodding which has been hitherto employed between the 20 connected levers when once engaged, and the mechanism for applying the brakes or releasing the signals, is entirely done away with. The mere action of connecting together the levers *a* produces directly the 25 release of the actuating member *o*. Further the mechanism for engaging the pulling member connected to the brakes or warning signals is located in the immediate vicinity of the axle carrying the scissor levers, so 30 that the entire apparatus can be easily enclosed in a casing away from frost and dust.

It is to be understood that the apparatus for direct connection of the locking mechanism of the levers *a* and the gear for applying the brakes and releasing the warning 35

signals may be constructed in very many different modifications.

What I claim is:

1. In automatic railway signaling apparatus of the type specified, the combination 40 with a pair of independently movable impact levers adapted to be actuated by track detents, a train device controlling member, two levers locking said member in its inoperative position, and means operatively connected to said impact levers for moving said locking levers into unlocking position when said impact levers are actuated.

2. In automatic railway signaling apparatus of the type specified, the combination 50 with two independently movable impact levers adapted to be operated by track detents on each side of the track, spring mechanism for operating the train brakes and warning signals, two levers pivoted scissors-fashion 55 each independently engaging said spring mechanism, and two rotary cams each adapted to actuate one of said two scissor levers, whereby the actuation of both impact levers is necessary to fully disengage said 60 spring mechanism in order to operate the train brakes and warning signals.

In testimony whereof I have signed my name to this specification in the presence of two subscribing witnesses.

JACQUES PIERRE DE BRAAM.
